UNITED STATES PATENT OFFICE.

ROBERT H. MUNGER, OF QUIMBY, IOWA.

UNCOUPLING-LEVER.

SPECIFICATION forming part of Letters Patent No. 600,549, dated March 15, 1898.

Application filed May 5, 1897. Serial No. 635,115. (No model.)

To all whom it may concern:

Be it known that I, ROBERT H. MUNGER, of Quimby, in the county of Cherokee and State of Iowa, have invented a new and Improved 5 Pin-Lifter Device for Car-Couplings, of which the following is a full, clear, and exact description.

This invention relates to means for lifting the coupling-pins of car-couplings of the 10 Janney type, and has for its object to provide a novel, simple, and practical device of the indicated character which will facilitate the free withdrawal of a coupling-pin either from the roof or the side of a car. 15 In the usual construction of pin-lifting devices the portion of the same that is operative at the side of the car frequently impedes the release of the coupling-pin from the roof of the car, particularly in cold weather, 20 when sleet or snow is frozen fast upon the rock-shaft or the side lever thereon, which afford means for lifting the coupling-pin from the side of the car, as the same rock-shaft is employed for elevating the coupling-pin both 25 from the roof and the side of the car.

The improved coupling-pin-lifting device comprises independently-operative mechanism at the side and on the roof of the car which permits of the easy and reliable lifting 30 at all times of the connected coupling-pin from either point mentioned and which may be quickly released for operation if at any time impeded by ice or snow.

The invention also provides means on the 35 roof of the car for temporarily maintaining the vertically-slidable coupling-pin in elevated position, so as to be automatically dropped by the impact of two car-couplings that are to be connected.

40 The invention further consists in the peculiar construction and combination of parts, as is hereinafter described, and pointed out in the claims.

Reference is to be had to the accompanying 45 drawings, forming a part of this specification, in which similar characters of reference indicate corresponding parts in all the figures.

Figure 1 is a side view of one end of a car having a coupling of the Janney type thereon and the improved pin-lifting mechanism 50 adjusted and lifting the coupling-pin from the car-roof. Fig. 2 is an end view of the car-

body having the improvements, the parts being in the position shown in Fig. 1. Fig. 3 is an enlarged perspective view of a main portion of the two-part rock-shaft for the improved pin-lifter and the side lever at one end of said shaft, together with a novel coupling-box for the two sections of the rock-shaft. Fig. 4 is an enlarged longitudinal sectional view of the rock-shaft coupling-box substantially on the line 4-4 in Fig. 5. Fig. 5 is a transverse sectional view of the rock-shaft and an end view of the coupling-box, the section being taken on the line 5-5 in Fig. 2. Fig. 6 is an end view of the rock-shaft, the lever thereon, and the supporting-box for the shaft seen in the direction of the arrow 1 in Figs. 2 and 3, the lever, however, being differently adjusted from the position it occupies in said figures; and Fig. 7 is an enlarged end view of the tripping-shaft on the roof of the car, the supporting bracket-stand therefore, and the tripping-lever thereon shown in full lines as adjusted to lift the car-coupling pin and in dotted lines as in position to drop said pin, the view being taken in the direction of the arrow 2 in Fig. 1.

In the drawings, A indicates a car-body, whereon the automatic car-coupling draw-head B is held by any approved means, said draw-head having a suitable coupling-pin C, vertically slidable in a perforation in the draw-head near the front of its link-receiving chamber.

The pin-lifting mechanism constituting the present improvements consists of a rock-shaft composed of two portions 10 and 10^a, the portion 10 of said shaft being horizontally supported to rock on the end of the car-body A in the bracket-boxes 11 and 12, the box 12, which is of a novel construction, being located near the side of the car-body, as indicated in Fig. 2. The section 10 of the shaft is mainly cylindrical in its body, but near the end which engages with the box 12 it is flattened to render it thinner and to produce two widened parallel sides, and on the outer extremity of said section a handle-lever 10^b is bent at a right angle thereto.

The bracket-box 12 comprises a flange b, projecting at a right angle to the base-plate upon which it is formed, and said flange has a transverse substantially circular aperture c

formed therein, which intersects the upright slot c' , produced in the flange near the base-plate. On the inner end of the section 10 of the shaft a coupling-box 13 is secured, said box being constructed in the form of a short cylindrical shell, preferably tapered at the end which is affixed to said section 10 of the shaft. Two ribs d are oppositely and longitudinally disposed within the box and may be either integral with the box or be attached to the box. The other section 10 a of the shaft is mainly cylindrical and is rotatably supported in axial alignment with the section 10 by bracket-boxes 14 15, properly spaced apart and secured upon the end wall of the car-body A.

On the end of the section 10 a that enters the coupling-box 13 a flattened connecting-leaf e is formed or secured and has parallel edges, the latter being adapted to loosely contact with the interior of the coupling-box and may impinge upon the ribs d at the opposite sides thereof, as will hereinafter be further explained. The opposite end of the section 10 a is furnished with an arm 16, shackled to the upper end of the coupling-pin C, as indicated at f in Figs. 1 and 2, and intermediately of the ends of the section 10 a another arm 17 is projected therefrom in the same plane and direction as the rock-arm 16, and it will be seen that when the handle-lever 10 b is pendent and the flattened portion of the section 10 of the rock-shaft occupies the slot c' of the bracket-box 12 the arms 16 17 will be raised and the pin C be lifted to release the knuckle of the coupling.

On the roof of the car-body A a tripping-shaft 18 is supported to rock in bracket-stands 19 20, the stand 19 being simply perforated laterally in its vertical member to receive the body of the shaft, said stand being located near the end wall of the car-body. The tripping-shaft where it engages with the apertured bracket-stand 20 is flattened, and at this end a right-angle bent handle-lever 21 is formed or secured. The aperture g in the bracket-stand 20 is circular and essentially similar to that in the bracket-box 12. The aperture g is connected with a slot h by an extension h' of said slot, the slot h being in this construction horizontally disposed, as shown in Fig. 7.

A short limb 18 a is formed or secured on the end of the tripping-shaft 18 outside of the bracket-stand 19, which limb is loosely connected at its lower end with the outer end of the arm 17 on the part 10 a of the rock-shaft 10 10 a , and it will be seen that when the handle-lever 21 is rocked upwardly the corresponding elevation of the rod 22 or its equivalent will so rock the shaft-section 10 a that the coupling-pin C will be lifted and thus release the draw-head of the car-coupling from a coupled connection with another coupling by withdrawing the pin from a locked engagement with the hinged knuckle of the coupling.

Referring to Fig. 6, it will be seen that the pin C has been elevated by an upward rocking movement of the handle-lever 10 b from a pendent position, this effect resulting from the contact of the ribs d in the coupling-box 13 with the edge portions of the leaf e of the shaft-section 10 a , whereby the latter is partly rotated in a proper direction for the elevation of the rock-arm 16 and the loosely-shackled pin C.

Should occasion require, the handle-lever 10 b may be temporarily retained in an upwardly-rocked position, as shown in Fig. 1 in dotted lines and Fig. 6 in full lines, if the flattened portion of the shaft-section is introduced within the transverse slot connecting the rounded aperture c with the vertical slot c' , as the sides of the flat portion of the shaft 85 will be then held from rocking by their contact with the walls of said connecting-slot enforced by the imposed weight of the handle-lever, so that the coupling-pin may thus be retained elevated until the lever 10 b is released.

The handle-lever 10 b may readily be adjusted to assume a pendent position, which will locate the ribs d in a horizontal plane, and as the arms 16 17 of the shaft-section 10 a 95 are projected outward when the coupling-pin C is in a lowered condition the upward rocking movement of said arms, due to a manipulation of the tripping-lever 21, whereby the tripping-shaft 18 is suitably rocked and the pin C elevated, may be effected without affecting the lever 10 b , the leaf e then moving away from the ribs d , as appears in Fig. 3.

Should it be necessary to temporarily adjust the handle-lever 21 so as to maintain it elevated and keep the pin C from dropping and thus facilitate the automatic coupled engagement of two side-latching car-couplings, this can be effected if the flattened portion of the tripping-shaft close to the handle-lever 110 be loosely interlocked with the walls of the short connecting-slot h' between the slot h and the aperture g in the bracket-stand 20, the weight of the inclined handle-lever conducting to the support of the same.

It will be seen that when the lever 21 is positioned as just explained a slight jar on the tripping-shaft 18 will permit said lever to drop from its vertical position, and this will allow the pin C to fall.

As the device located on the roof of the car-body A for lifting the coupling-pin C may be operated and yet not interfere with the device provided for elevating the pin from the side of the car, it will be evident that any obstruction which might render the latter lifting device difficult to move will not interfere with the detachment of two coupled cars from the roof of either coupled car. This is a very essential provision, as in case of an emergency 130 a train can be cut apart while moving, and the detachment will be effected with safety to the operator.

Having thus described my invention, I

claim as new and desire to secure by Letters Patent—

1. A pin-operating device for car-couplings, comprising a shaft having a flat section at one bearing-point, a supporting-bearing therefor containing a circular opening, and a slot which is tangent to said circular opening and at its center communicates therewith, a second shaft in line with this and having an arm attached to the pin, and a slack connection between the two shafts, permitting the pin-connected shaft to be oscillated without oscillating the other.
2. A pin-operating mechanism for car-couplings, comprising a shaft mounted upon the end of the car and consisting of two separate sections, one section having an arm attached to the pin and the other section having an operating crank-handle, and slack connections between the two sections which will permit the pin-lifting arm to be raised without rotating the other section.
3. A pin-operating mechanism for car-couplings, comprising a shaft journaled across the face of the car and having an arm connected to the pin to raise it, a shaft in line with and having slack connection thereto which will permit the first shaft to be oscillated to raise the pin without oscillating the other shaft, the outer end of the second shaft having a flattened section and a bearing therefor having a circular opening and a notch or slot communicating therewith and adapted to re-

ceive the flattened section of the shaft to lock it in position.

4. In a pin-lifter, the combination with an upwardly-slidable coupling-pin, of a two-part rock-shaft on the end of a car, the inner part of said shaft having a crank-arm loosely shackled to the coupling-pin, the outer part being supported to rock in alinement with the inner cranked portion, and connected therewith by a slack joint which permits the inner part oscillating to lift the pin without operating the outer part, said outer part having a handle-lever, and a device engaging the shaft near the handle-lever, and adapted to temporarily hold the lever and coupling-pin elevated, substantially as described.

5. A pin-lifter for car-couplings, comprising a two-part rock-shaft supported to rock on the end of the car, one part of said shaft having a crank-arm loosely shackled to the coupling-pin, the other part of said shaft being flattened at the outer end and provided with a handle-lever, a coupling-box loosely connecting the two sections of the rock-shaft, and means for loosely connecting an arm on the cranked section of the rock-shaft with a pin-lifting device on the roof of the car, substantially as described.
